UNITED STATES PATENT OFFICE.

THOMAS ALEX. BOYD AND HAROLD ARTHUR BOYD, OF SHETTLESTON, NEAR GLASGOW, SCOTLAND.

TWISTING FRAME FOR THREADS OR FILAMENTS.

Application filed September 8, 1923. Serial No. 661,588.

To all whom it may concern:

Be it known that we, THOMAS ALEXANDER BOYD and HAROLD ARTHUR BOYD, both subjects of the King of Great Britain and Northern Ireland, and residing at Shettleston, near Glasgow, Scotland, have invented a certain new and useful Improvement in Twisting Frames for Threads or Filaments, of which the following is a specification.

10 This invention refers to an improved machine for imparting spin or twist to sets of threads or filaments, such for example as filaments of artificial silk, drawing them from a carrier and twisting and winding them on to a bobbin.

According to the invention, the threads or filaments are drawn from a rotating carrier which unwinds the threads or filaments without itself imparting any twist to them. 20 The threads or filaments pass directly from the carrier to a twisting or flyer spindle which draws them from the carrier, twists them and winds them on to a bobbin. The threads or filaments are drawn off substantially at right angles to the axis of the carrier which is rotated at a fixed speed in relation to the speed of the twisting spindle and so disposed that the twist passes from the spindle to the face of the carrier, tending to lick up the several threads or filaments of the set to be twisted together.

30 The invention comprises means for simultaneously starting and stopping the twisting spindle and the carrier corresponding to an individual spindle.

The invention is illustrated in part elevation part vertical section in the figure of the accompanying drawing.

As shown, 1 denotes a spindle rail carried on a framing disposed horizontally and extending from end to end along the front of the machine. On the rail 1, at suitable distances apart, we mount a row of vertical flyer spindles 2 which are each driven by a cord or tape 3 from a tin roller or driving cylinder 4, disposed horizontally and parallel with the rail 1. On a bracket 5 fixed on the rail 1 below and behind each spindle 2 we joint a cord tensioning device comprising a lever 6 having an arm projecting towards the tin roller 4 and carrying near its inner end 6' a tension pulley 7 having its axis horizontal and parallel with the tin roller 4. The cord 3 is led from the tin roller 4 over the tension pulley 7 to the

wharve 2' on the spindle 2 and thence to and around the tin roller 4. The tension pulley 7 is held at its highest point by a releasable catch 8 which engages at 6² the lever 6. When the catch 8 is disengaged 60 and the tension pulley 7 is lowered, the cord 3 is untensioned and gripped, thereby braking and stopping the spindle 2. The cord 3, as it proceeds from the tin roller 4 to the spindle 2, passes between a stationary 65 and a movable grip. The upper grip 9' is stationary and is formed on the bracket 5. The lower or movable grip 6³ is formed on the front end of the lever 6 which front end rises to grip the cord as the inner end 70 of the lever falls. Below and in front of the tin roller 4 on a fulcrum parallel therewith is fixed a rod 10 extending from end to end of the frame. At one side of each lever 6 we mount on the rod 10 a bell crank 75 11 having on its vertical arm 11' a spindle step 12. The horizontal arm 11² of the bell crank 11 extends below the tin roller 4 and carries a weight 13. In the step 12 we mount a vertical spindle 14 extending upwards to 80 a creel shaft hereafter described. Near the lower end 14' of the vertical spindle 14 we mount a wharve 16 with several V-grooves of unequal diameter and at about the same height we provide integral with the wharve 85 2' an additional wharve 2² having V-grooves also of unequal diameter to receive a cord 15 by which the spindle 14 is driven. By means of the bell crank 11 the spindle 14 is pressed away from the spindle 2 and the 90 cord 15 maintained taut, the speed of rotation of the spindle 14 depending on the selection of V-grooves engaged by the cord 15. At a suitable distance above the spindle 2 and behind the same we mount a pair of 95 creel rails 18, disposed horizontally, parallel with the tin roller 4 and at a suitable distance apart. On these creel rails 18 we mount in bearings 19 a creel shaft 20 the axis of which is substantially perpendicular 100 to the axis of the spindle 2. On the creel shaft 20 we mount a worm wheel 21 meshing with a worm 22 on the upper end 14² of the spindle 14. The upper end 14² of the spindle 14 is supported in an oscillating bearing 23 carried in an oil box 24 bolted to the front creel rail 18. On the forward end 20' of the shaft 20 we mount a carrier 105 25 on which filaments 26 have been wound, said carrier being located substantially on 110

the line of the axis of the spindle 2. The set of filaments 26 is carried downwards from the carrier 25 to the flyer spindle 2 and twisted and wound on to the twisting bobbin 27 coaxial with said spindle 2. When the flyer spindle 2 is started, it drives the vertical spindle 14, the shaft 20 and the carrier 25 which latter, as it rotates, delivers the set of filaments 26 to the spindle 2. As the spindle 2 rotates, the twist passes upwards on to the set of filaments 26 and tends to lick up the filaments as they are twisted and pass downwards. When the flyer spindle 2 is started or stopped, the carrier 25 is instantly started or stopped. The bobbin 27 on the flyer spindle 2 may be traversed up and down by ordinary traverse mechanism.

We claim:—

1. In a twisting frame for twisting sets of filaments, in combination, a twisting spindle, for twisting the filaments and winding them on to a bobbin, a rotary shaft operatively connected to said twisting spindle and a carrier from which the filaments to be twisted are drawn directly, said carrier being rotatable with said shaft and arranged to deliver the filaments to said twisting spindle without itself twisting the filaments, said carrier being so disposed in relation to said twisting spindle that the twist from said twisting spindle passes to the face of the carrier and licks up the filaments of the set to be twisted together.

2. In a twisting frame for twisting sets of filaments, in combination, a twisting spindle for twisting filaments and winding them on to a bobbin, a rotary shaft operatively connected to said twisting spindle, the axis of said shaft being substantially perpendicular to the axis of said twisting spindle, and a carrier from which the filaments to be twisted are drawn directly to said twisting spindle, said carrier being located substantially in the line of the axis of said twisting spindle.

3. In a twisting frame for twisting sets of filaments, in combination, a twisting spindle for twisting filaments and winding them on to a bobbin, a rotary shaft operatively connected to said twisting spindle and having its axis substantially transverse to the axis of said twisting spindle, a carrier from which the filaments to be twisted are drawn

directly, said carrier being rotatable with said shaft and arranged to deliver the filaments to said twisting spindle without itself twisting the filaments, and means for starting and stopping simultaneously said twisting spindle and said carrier.

4. In a twisting frame for twisting sets of filaments, in combination, a twisting spindle for twisting filaments and winding them on to a bobbin, a flexible transmission element for driving said twisting spindle, a rotary shaft, having its axis substantially perpendicular to the axis of said twisting spindle, a spindle geared to said shaft, an operative connection between said twisting spindle and said last named spindle, a carrier for filaments, said carrier being rotatable with said shaft and located in about the line of the axis of said twisting spindle, and means operative to render taut or slacken said element for starting or stopping simultaneously the rotation of said twisting spindle and said carrier.

5. In a twisting frame for twisting sets of filaments, in combination, a twisting spindle for twisting the filaments and winding them on to a bobbin, a rotary shaft having its axis substantially transverse to the axis of said twisting spindle, an intermediate spindle parallel to said twisting spindle and geared to said shaft, means including a flexible transmission element for rotating said twisting spindle, a flexible driving connection between said twisting spindle and said intermediate spindle, a carrier for filaments, said carrier being rotatable with said shaft and located in about the line of the axis of said twisting spindle, a tensioning device active on said transmission element, and a catch operatively connected with said tensioning device and releasable to free said tensioning device for said transmission element to discontinue rotation of said spindles and shaft.

In testimony whereof we have signed our names to this specification in the presence of two subscribing witnesses.

THOMAS ALEX. BOYD.
HAROLD ARTHUR BOYD.
